UNITED STATES PATENT OFFICE.

FORREST A. HEATH, OF JERSEY CITY, NEW JERSEY, ASSIGNOR TO HEATH CARBURETER CORPORATION, A CORPORATION OF NEW YORK.

CARBURETER.

1,287,990.

Specification of Letters Patent. Patented Dec. 17, 1918.

Application filed March 10, 1915, Serial No. 13,400. Renewed May 7, 1918. Serial No. 233,169.

To all whom it may concern:

Be it known that I, FORREST A. HEATH, a citizen of the United States, and resident of Jersey City, in the county of Hudson and 5 State of New Jersey, have invented certain new and useful Improvements in Carbureters, of which the following is a specification.

My present invention relates to carbureters of the type in which an explosive mixture for combustion in motor cylinders is made by mechanically comminuting or atomizing liquid fuel and diffusing it in predetermined quantities and proportions 15 in an air draft which is utilized as a carrier of the fuel and the supporter of combustion. Such devices commonly embody an air inlet, a gasoline inlet, a mixing chamber and a throttle or damper for regulating 20 the volume of the mixture which will be drawn inward in response to the suction of the motor cylinder.

My invention is embodied in a simple compact device of this class, in which the 25 gasoline supply and the air supply are controlled by separate metering devices operated interdependently by means of a single controller, so that the total volume of the mixture can be adjusted from zero 30 up to the maximum requirements of the motor. Preferably the gasoline metering device is such that all adjustment movements produce directly proportional increases in the gasoline inlet area, while the 35 air inlet of the throttle is provided with an obstruction or baffle so that the increase in air supply is dependent on the shape and position of the obstruction with reference to the throttle movement. This is predetermined 40 so as to give the best percentage of gasoline for each volume of the mixture and in practice the baffle keeps the increase of air inlet area much less than proportional from closed throttle up to say $\frac{1}{4}$ or $\frac{1}{2}$ open 45 throttle. By thus applying the variable metering to the large volume constituent—the air—I avoid the necessity of microscopic accuracy which is necessary where the richness variation is effected by variable 50 metering of the minute quantity constituent—the gasoline.

By arranging the throttle opening in the form of an annulus having an axis parallel with and preferably in alinement with the 55 gasoline metering device, it becomes pos-

sible to make the adjusting movement of the one predetermine and control the adjusting movement of the other in a very simple and reliable way.

I preferably make the air valve seat 60 which carries the air metering surface, adjustable independently of the throttle so that the initial throw of the gasoline meter device may be made greater or less thereby 65 changing the initial or basic ratio of gasoline to air. This adjustment does not interfere with the function of the air metering baffle in varying the relative richness of such mixture for the various intermediate 70 throttle positions.

I also arrange for obtaining maximum air inlet velocities and maximum vacuum in the initial mixing chamber under closed-throttle conditions, so as to increase the effectiveness of the atomizing and to promote 75 evaporation. To this end I arrange the throttle inlet in the form of a relatively narrow annular opening or slit located below the gasoline inlet nozzles. In the form shown, the circumference of this slit is 80 about sixteen times the height at maximum lift. This projects the air as a uniform thin annular sheet converging upwardly at high velocity toward the transversely projected gasoline jets. The air metering 85 baffle tends to give an upward deflection to the air even at wide open throttle. By arranging this air inlet slit as an annulus at the bottom of the carbureting chamber, any excess of gasoline drains to the nearest edge 90 thereof for most effective re-atomizing and evaporation, instead of tending to drain into one locality or to a position below the incoming air draft.

In order to keep up the standard maximum evaporation and atomizing under open 95 throttle conditions where the volume of the mixture is large and the vacuum is small, I arrange above the gasoline inlet and between it and the engine a mixing atomizer, 100 the efficiency of which is adapted to increase when the volume of mixture increases. Preferably this includes inclined or helical surfaces adapted to give the draft a spiral whirl, and coöperating transverse members 105 against which the whirling draft impinges.

By reason of the above referred to slit-like proportions of the air inlet, the total throttle lift is relatively minute, say one-fourth of an inch from tight closed to wide 110

open throttle. Hence, I preferably employ a motion multiplying device, preferably a cam slot, between the throttle and the manually operated controller so that the actual 5 manual movement for adjustment will be many times the resultant lift of the throttle.

I also arrange for automatically opening and closing the gasoline supply valve by means of the incoming air current instead of 10 by hand, or by the level of the gasoline in a supplemental chamber, as in the ordinary float feed carburetors. Thus any substantial 15 intermission in the suction will result in instant shutting off of the gasoline. The arrangement is preferably such that under 20 normal conditions the air current will hold the gasoline valve open to the fullest extent permitted by the air throttle adjustment. Hence the gasoline metering device may be 25 carried by this gasoline valve and yet during operation its extent of opening will be determined exactly by, and in fact may be identical with the throttle adjustment and throw, instead of being controlled by the variable vacuum in the mixing chamber.

The above and other features, such as arranging the gasoline nozzles as a plurality of minute radial orifices projecting the gasoline transversely of the air draft; closing 30 these orifices by means of a sliding plug valve adapted to engage a substantial broad seat, shutting off the supply of gasoline below the orifices; and forming the gasoline metering pin so that its maximum metering 35 diameter is its extreme tip, and the variation metering of the gasoline is affected entirely by the longitudinal divergence of the walls of the gasoline conduit, will be more fully evident from the following detailed 40 description of a practical embodiment of my invention, shown in the accompanying drawings in which—

Figure 1 is a side elevation of the complete device with interior details shown on 45 dotted lines,

Fig. 2 is a top plan view of Fig. 1,

Fig. 3 is a bottom plan viewed from below,

Fig. 4 is a vertical section on the line 4—4, 50 Fig. 2,

Fig. 5 is a top plan view of the throttle,

Figs. 6 and 7 are perspective views of parts shown in the preceding figures,

Fig. 8 is an enlarged view of the air inlet 55 with the variable metering effect diagrammatically indicated thereon and

Fig. 9 is an enlarged view of the gasoline valve and metering device.

The carburetor comprises a suitable case 60 in the lower part 1 of which is the carbureting chamber and the upper part 2 is a homogenizing or mixing chamber.

The former is preferably cylindrical and has fitted within it a cylindrical throttle 65 valve 3, adapted for finely graduated verti-

cal adjustment by means of the handle 5 engaging the circumferential cam slot 6.

In the axis of this throttle are arranged the gasoline supply jets, closing valve and 70 metering device.

A drop yoke comprising vertical members 7, 7 and a transverse bridge or support 8, preferably cast integral with casing 1, is formed with a central screw threaded opening 9, into which is screwed the gasoline 75 nozzle 10. The latter has an axial gasoline passage 11, closed at the lower end by screw plug 12. This passage is constricted at 13, to substantially the cross section required for adequate maximum supply of gasoline. 80 This feature is of considerable importance because in commercial practice, carburetors are frequently applied on automobile motors in which the maximum speed ranges are quite different and in the case of exceptionally high speed motors, the injector effect at very high speed, say 2500 to 3500 revolutions per minute, has a tendency to produce overrichness or flooding which can be prevented by making the constriction at 13 such 90 as will permit passage of only the maximum desired supply of gasoline. Above this constriction, there is a slightly diverging portion 14, then a cone valve seat 15 of substantial width and having a suitable angular divergence preferably about 30 degrees. Above the valve seat, is the enlarged cylindrical chamber 16, provided with a plurality of radially directed gasoline jets 17. The chamber 16 forms a vertical guide for the 100 stem 18 of the combined gasoline cut-off and metering valve, which is provided with a disk 19, adapted to abut against the septum 20, which is carried by the throttle 3. If desired, the valve may be provided with a 105 supplemental guide 21, extending through a guide passage 22, in said septum 20.

Below the disk 19, the stem 18 is formed for close but substantially frictionless fit in the guide passage 16, and with a conical 110 valve 25 fitting the seat 15. As this valve must be accurate yet frictionless, I prefer to dress the surface of the valve for its most accurate fit at the lower, smaller end, so that in practice, as the parts wear, the fit 115 will become gradually perfected upwardly from that point. The metering pin 26 projects below the valve and is preferably integral with it. It extends into the conical gasoline passage 14, preferably to the point 120 of junction with the constriction 13 when the valve is seated. In the seated position, the extreme lower end 24 of the metering pin fits this cross-section closely but frictionlessly. It need not be water tight.

For best operation in case where the carburetor is designed for proper capacity to suit a particular motor of given speed range and volume requirement, the divergence of the walls of passage 14 must be proportioned 130

with reference to the maximum lift of the pin so that the annular area for gasoline escape will never be greater than the area of the constricted inlet 13. This is because the 5 area of the outlet controls the flow, only so long as it is smaller than the inlet. In the arrangement shown, the diameter of the diverging portion 14 at the uppermost position of the tip of the pin should never exceed the diameter of the constricted portion 10 13 by more than about 5 to 4.

I preferably form the lower end of the metering pin say for one third of its length, on a taper which is the same as that of passage 14. By filing the end of the pin to get 15 a longer or shorter frustum for this cone tip, I can predetermine what region and what cross-section of passage 14, will be utilized for the metering, thus predetermining with 20 great accuracy the range of quantities of gasoline to be metered by a given lift of the metering pin.

Gasoline is supplied by a simple connection through a transverse passage 23. The 25 vacuum created by the engine suction at low throttle, and the injector effect at high engine speeds with wide open throttle may be utilized to draw the gasoline through this passage even when the reservoir is located 30 below the level of the jet outlet, but other things being equal, the supply is preferably from a reservoir located somewhat above the level of the gasoline jets 17, or otherwise arranged to deliver gasoline to said jets under 35 a slight pressure, say one-half pound to one pound and one-half per square inch. In the proportions shown, this will give a static pressure of say one or two ounces, upon the under side of the valve surfaces 24, 25 when the valve is not seated, and say half that when it is seated. The total weight of 40 the valve is made enough greater than the static pressure of the gasoline to make it normally self-seating by gravity against 45 said pressure, say an ounce or so heavier than the pressure.

The area and weight of the disk will be 50 designed with reference to the velocity and lifting power of the incoming air, so that, except possibly for very low engine speed 55 with wide throttle opening, the valve will always be lifted and held firmly against the abutment afforded by septum 20. Thus under all normal conditions the lower end or 60 metering point 24 of the pin will always have its position predetermined, and fixed by the position of the throttle which carries 65 said septum 20. With a metering device proportioned as shown in Fig. 9, the device 70 will give an increased amount of gasoline, approximately proportional to the lift of the 75 throttle.

As pointed out above, it is necessary in 80 devices of this class to meter one of its constituents disproportionately to the other, in

order to vary the richness of the mixture, and in accordance with my present invention, I apply this variable metering to the larger quantity constituent—the air. To this end, I provide a disk like valve seat 28 70 threaded upon the gasoline stem 10. In the proportions shown in the drawing, this gives an annular air inlet which, at wide open throttle has a peripheral extent about 16 times the maximum throttle lift. Even allowing for the supports 7, 7, which cut off 75 part of the circumference, this proportion is fully 12 to 1. For half throttle, it will be 24 to 1, for quarter throttle 48 to 1, and for eighth throttle, 96 to 1. Thus, under the 80 exacting conditions of nearly closed throttle, the slit is extremely narrow and adapted to supply air in the thinnest possible sheet of highest possible velocity, thus giving maximum conflict and atomizing action relative 85 to the transverse gasoline jets from the orifices 17 and also adequate lifting effect on valve disk 19.

The variable metering of the air to get the required disproportionate percentages of air 90 and gasoline is effected by means of a carefully pre-designed circular baffle 29, adjacent the air inlet slit and extending upward for say one-fourth the total lift of the throttle. The effect which this baffle has in preventing 95 increase of effective air inlet area from being proportional to the lift of the throttle will be more evident from Fig. 8, which is a greatly enlarged view showing the parts, movements and areas involved. From said 100 figure it will be evident that for the first one-eighth throttle lift, say $\frac{1}{8}$ inch, the metering slit is measured from a' to b and the air inlet area increases in direct proportion to the lift of the throttle. At this 105 point however, the point c on the surface of the baffle becomes the nearest point to the lower edge of the throttle and the line $a'-c$ being then the minimum opening, is necessarily the metering opening. From this 110 point up to a^2 the air inlet areas continue to increase with increasing lift of throttle, but the increase is in a very much smaller ratio to the lift, so that at a^2 the width of the air slit a^2-d , is about 50% of what it 115 would be for a direct proportion. From this point on the effective width of air slit for successive positions of the lifting throttle, are shown at a^3-d , a^4-d , a^5-d , etc. For each of these latter positions, it will be 120 seen that the effect of the baffle becomes less and less and each unit lift gives nearer and nearer proportional increase of air opening, the difference between the throttle lift and increase of throttle area at a^7 and a^8 being 125 scarcely measurable.

The seat 29 with its baffle are made manually adjustable to a very slight extent by means of the lever projection 30. It will be seen that these adjustments give only a very 130

4

slight variation in the initial relation of the gasolene valve abutment on septum 20, thus securing slightly greater initial lift of the metering pin in response to the initial movement of opening throttle. This adjustment is used mainly for accurately predetermining the best proportions of mixture for idling conditions in different kinds of weather, or season, or heating of the motor.

10 The idling condition being the most exacting and the predetermined basic richness of mixture suitable therefor having been obtained by valve seat adjustment, the metering devices provided by my invention will properly vary the proportions for the varying conditions of load and motor speed.

By the above described arrangement, an extremely thin converging cone-shaped sheet of air is drawn in at high velocity; the 20 gasolene is projected across this conical air sheet to the best advantage for atomizing; the maximum vacuum for effective evaporation is greatest under the most trying condition, namely, that of lowest throttle; projected or condensing gasolene drains directly to the nearest portion of the slit on the upper side thereof so that it will be to the greatest possible extent licked off from the lower edge of the throttle without escaping therefrom.

30 The secondary atomizing and mixing appliances in the upper part, 2, of the casing, are useful under all conditions but are especially adapted for greatest efficiency 35 when the throttle is widest open. At such times, the vacuum in the initial mixing chamber is smallest, while at such times the volume of the air draft is greatest. Hence, I employ as the secondary mixing appliance 40 one which is most effective in connection with large volume and high speed draft. For this purpose, the vertical throttle wall beneath the septum 20 is provided with suitable radial outlets 31, which projects the 45 draft in the path of inclined, preferably helical surfaces which may take the form of ribs 32, cast integral with the wall of the casing. In order to prevent localizing a vacuum above the septum 20 such as would 50 tend to lift the throttle and disturb the adjustment thereof, I may provide the latter with inclined or helically directed openings 54 adapted to relieve the vacuum and also whirl the center of the draft preferably in 55 the same direction as the ribs 32.

This arrangement gives the draft a helical commingling action, tending to throw the larger particles or globules of gasolene outwardly against the walls by centrifugal 60 force. Those which are small enough to be carried forward by the draft are subject to the action of transverse surfaces afforded by the radial, spoke-like members 33. These 65 completely break up all tendency to stratifying or unequal distribution of the gasolene

and they further break up any unatomized particles in the draft. The general result is that the core or interior of the air draft which is farthest remote from the friction retardation of the walls is a practically 70 homogeneous mixture with a large percentage of its hydro-carbon actually evaporated to gaseous condition and the remainder so minutely atomized as to be a satisfactory approximation of gas.

75 In the foregoing description and in the following claims I use the word gasolene in a broad sense as including the wide range of hydrocarbon mixtures now popularly designated by this name, since I have used 80 my carburetor successfully for starting as well as running automobile motors on commercial 54° gasolene and under some conditions, on kerosene.

I preferably inclose the air inlet and also 85 afford protection for the cam slot of the throttle by means of a sheet metal casing 35, applied over the bottom of the device and secured by screws 36 to the yoke 8.

As a supplemental starting device for 90 priming the draft for starting the motor when cold, I may arrange a tap pipe 37 controlled by hand operated cock 38 discharging into the sheet metal case referred to. A relatively large amount of gasolene 95 may be injected at this point in this way without flooding the carburetor beyond the limits of easy control through the throttle in the usual way.

100 What is claimed is:—

1. In a carburetor of the class described, a cylindrical case member, a cylindrical air throttle longitudinally adjustable therein, a circular seat at right angles to the axis of said throttle and concentric therewith, a 105 gasolene supply passage and nozzle substantially in the axis of said throttle above said seat, a gasolene valve having a disk adapted to be lifted by the air draft, a stop for said valve movable interdependently with said 110 throttle, whereby in operation the extent of movement of the gasolene valve will be limited by the movement of the throttle.

2. In a carburetor of the class described, a cylindrical case member, a cylindrical air 115 throttle, longitudinally movable therein, a circular seat at right angles to the axis of said throttle, and concentric therewith, a gasolene supply passage and nozzle substantially in the axis of said throttle above said seat, a gasolene valve, a disk adapted to be lifted by the air draft and carrying said valve, a stop for said valve carried by said throttle whereby, in operation, the extent of movement of the gasolene valve will be 120 equal to the lift of the throttle.

3. In a carburetor of the class described a gasolene supply passage comprising an inlet adapted to permit flow of gasolene equal 125 to the maximum requirements of the car. 130

bureter, a diverging passage above said inlet, a lateral vent for the gasolene, a draft operated metering pin longitudinally movable in said diverging passage, formed and arranged so that the lower end of said pin determines the minimum constriction and metering point of the gasolene, in combination with a throttle in the form of a cylinder surrounding said gasolene supply passage, 5 means for longitudinally moving said cylinder to open and close the air inlet, a member carried by said throttle cylinder adapted to limit the opening movement of the gasolene metering pin by the movement of the 10 throttle, in combination with means for obstructing the air inlet passage to meter the air variably with respect to the gasolene supply and thereby insure predetermined variations of richness of the air and gasolene mixture for the different volumes thereof.

4. In a carbureter of the class described a gasolene supply passage comprising an inlet adapted to permit flow of gasolene equal 25 to the maximum requirements of the carbureter, a diverging passage above said inlet, lateral deflecting means for the gasolene jet, a metering pin longitudinally movable in said diverging passage, formed and arranged so that the lower end of said pin determines the minimum constriction and metering point of the gasolene throughout the range of operative positions thereof, in combination with a hollow sleeve throttle 35 surrounding said gasolene supply passage, means for longitudinally moving said sleeve to open and close the throttle, a member carried by said throttle adapted to permit regulated movement of the gasolene metering pin 40 equal to the adjusting movement of the throttle.

5. A carbureter comprising a hollow casting, a transverse support across the lower end, an axial gasolene nozzle mounted on 45 said support, an air inlet throttle seat adjustable on said gasolene nozzle, a longitudinally adjustable throttle sleeve concentric with said parts and longitudinally movable within said casting, a symmetrical movable 50 gasolene controller in said gasolene nozzle, and means carried by said throttle adapted to limit the opening of said gasolene controller by increase of the extent of opening of said throttle.

55 6. A carbureter comprising in combination, a longitudinally extending gasolene nozzle, and surrounding air throttle together with a transverse throttle seat below said nozzle all concentrically supported in fixed 60 relation, a draft operated gasolene metering valve, mounted in and guided by said gasolene nozzle and a stop carried by and moving with said throttle to prevent opening of the gasolene device to a greater extent than 65 the throttle opening.

7. In a carbureter of the class described a gasolene supply passage comprising an inlet adapted to permit flow of gasolene equal to the maximum requirements of the carbureter, a diverging passage above said inlet, 70 a lateral vent for the gasolene, a draft operated metering pin longitudinally movable in said diverging passage, formed and arranged so that the lower end of said pin determines the minimum constriction and 75 metering point of the gasolene throughout all adjustments thereof, in combination with a cylindrical throttle for controlling the draft at the air inlet only.

8. In a carbureter of the class described a gasolene supply passage comprising an inlet adapted to permit flow of gasolene equal to the maximum requirements of the carbureter, a diverging passage above said inlet, lateral deflecting means for the gasolene jet, 85 a metering pin longitudinally movable in said diverging passage, formed and arranged so that the lower end of said pin determines the minimum constriction and metering point of the gasolene throughout all 90 adjustments thereof, in combination with a cylindrical throttle for controlling the draft at the air inlet only.

9. A carbureter having two co-axial rotatable members spaced apart to form an annular air inlet, one of said members being in the form of a sleeve and the other of said members being in the form of an end wall, and each of said members being adjustable toward and from the other by a rotation 95 about the common axis.

10. A carbureter having two co-axial rotatable members spaced apart to form an annular air inlet, one of said members being in the form of a sleeve and the other of 100 said members being in the form of an end wall, and each of said members being adjustable toward and from the other by a rotation about the common axis, the rotation of one of said members through a given arc 105 effecting a considerably greater axial movement than is effected by a corresponding rotation of the other member.

11. A carbureter having two co-axial rotatable members spaced apart to form a passage therebetween, means for effecting a comparatively slight axial movement of one of said members toward and from the other member upon the rotation thereof to provide a fine adjustment of the effective size of said 115 passage, and means for effecting a materially greater axial movement upon a corresponding rotation of the other member to permit a coarse adjustment of the effective size of said passage.

12. A carbureter having two co-axial rotatable members spaced apart to form a passage therebetween, one of said members being in the form of a sleeve and the other of 120 said members being in the form of a trans- 125

verse wall adjacent to one end of said sleeve, means for effecting a comparatively slight axial movement of one of said members toward and from the other member upon the 5 rotation thereof to provide a fine adjustment of the effective size of said passage, and means for effecting a materially greater axial movement of the other member to permit a coarse adjustment of the effective size 10 of said passage.

13. A carbureter having a centrally disposed liquid fuel inlet, an annular air inlet encircling the same, a valve controlling said liquid fuel inlet, an annular sleeve movable 15 axially to control the size of said air inlet, means connected to said valve for automatically opening the latter by the passage of the gaseous draft current through said carbureter, and means for varying the limit for 20 the opening movement of said valve in accordance with the position of said air inlet controlling sleeve.

14. A carbureter having a liquid fuel inlet, an annular air inlet, a member movable 25 in the direction of the movement of fluid through said carbureter for controlling said air inlet, a member for controlling said liquid fuel inlet, and means whereby the axial opening movement of the latter is 30 limited by the axial movement of the other member, without preventing independent closing movement thereof.

15. A carbureter having a sleeve and a member toward which said sleeve may move 35 axially, said member presenting a surface adjacent to one end of said sleeve and spaced therefrom to form an annular draft passage, the relative contours of said surface and the end of said sleeve being such that equal 40 axial movements of said sleeve give variable increases or decreases in the size of said passage.

16. A carbureter having a sleeve and a member normally spaced therefrom, one of 45 said members being axially movable toward and from the other to vary the size of the annular draft passage therebetween, the said member presenting a constricting surface whereby equal axial movements of one member produce unequal corresponding increases 50 or decreases in the size of said annular passage.

17. A carbureter having a sleeve and a member normally spaced therefrom, one of 55 said members being axially movable toward and from the other to vary the size of the annular draft passage therebetween, the said member presenting a constricting surface whereby equal axial movements of one 60 member produce unequal corresponding increases or decreases in the size of said annular passage during one portion of its range of movement and produces equal variations in the size of said passage for equal move-

ments of said member when in another portion of its range of movement.

18. In a carbureter of the type adapted to control the power and speed of variable speed explosive motors, a suitable casing having a draft passage through which the 70 draft is adapted to be drawn by the suction of the motor, means for supplying a liquid fuel jet intermediate the ends of said draft passage, a draft controlling throttle valve adapted to variably constrict said draft 75 passage on the draft inlet side of said jet, thereby subjecting the liquid fuel jet to the maximum vacuum available through variable throttling of the draft under varying conditions of motor speed and load, a meter- 80 ing device for varying the liquid fuel supply, a controller for positively actuating the throttle, a stop movable interdependently with the throttle and a disk on the fuel meter actuated by flow of the draft currents 85 to hold said fuel meter open to the full extent permitted by said stop during normal operation of the device, but permitting independent self-closing of said fuel meter when the draft current fails, said fuel meter being 90 formed and arranged to vary the area of the fuel metering passage substantially uniformly and proportionally throughout the range of its adjusting movement, and said throttle valve being formed and arranged to 95 vary the area of the air metering passage in variable proportion.

19. In a carbureter of the type adapted to control the power and speed of variable speed explosive motors, a suitable casing 100 having a draft passage through which the draft is adapted to be drawn by the suction of the motor, means for supplying a liquid fuel jet intermediate the ends of said draft passage, a draft controlling throttle valve 105 adapted to variably constrict said draft passage on the draft inlet side of said jet, thereby subjecting the liquid fuel jet to the maximum vacuum available through variable throttling of the draft under varying conditions of motor speed and load, means for whirling and mixing the draft in said draft 110 passage on the outlet side of said fuel jet, a metering device for varying the liquid fuel supply, a controller for positively actuating 115 the throttle, a stop movable interdependently with the throttle and a disk on the fuel meter actuated by flow of the draft currents to hold said fuel meter open to the full extent permitted by said stop during normal 120 operation of the device, but permitting independent self-closing of said fuel meter when the draft current fails, said fuel meter being formed and arranged to vary the area of the fuel metering passage substantially 125 uniformly and proportionally throughout the range of its adjusting movement, and said throttle valve being formed and arranged to

ranged to vary the area of the air metering passage in variable proportion.

20. In a carbureter of the type adapted to control the power and speed of variable speed explosive motors, a suitable casing having a draft passage through which the draft is adapted to be drawn by the suction of the motor, means for supplying a liquid fuel jet intermediate the ends of said draft passage, 10 a draft controlling throttle valve consisting of a hollow cylindrical member and transverse member mounted for relative opening and closing movement to variably constrict said draft passage on the draft inlet side of 15 said jet, thereby subjecting the liquid fuel jet to the maximum vacuum available through variable throttling of the draft under varying conditions of motor speed and load, means for whirling and mixing the draft in 20 said draft passage on the outlet side of said jet, said means including an enlarged mixing chamber having walls converging toward the exit opening and relatively narrow oblique ribs on said walls for inducing whirling 25 motion in said draft and, adjacent the outlet, thin open spaced transversely extending members against which the whirling mixture is adapted to impinge obliquely, a metering device for varying the liquid fuel 30 supply, a controller for positively actuating the throttle, a stop movable interdependently with the throttle and a disk on the fuel meter actuated by flow of the draft currents to hold said fuel meter open to the full extent 35 permitted by said stop during normal operation of the device, but permitting independent self-closing of said fuel meter when the draft current fails, said fuel meter being formed and arranged to vary the area 40 of the fuel metering passage substantially uniformly and proportionally throughout the range of its adjusting movement, and said throttle valve being formed and arranged to 45 vary the area of the air metering passage in variable proportion.

21. In a carbureter of the type adapted to control the power and speed of variable speed explosive motors, a suitable casing

having a draft passage through which the draft is adapted to be drawn by the suction 50 of the motor, means for supplying a liquid fuel jet intermediate the ends of said draft passage, a draft controlling throttle valve on the draft inlet side of said jet, said valve comprising a circular draft inlet member 55 and a coöperating transverse disk adapted to close said inlet arranged for relative opening and closing movement in a direction parallel with the axis of said disk to variably constrict said draft opening; means for 60 whirling and mixing the draft on the outlet side of said jet, said means including an enlarged mixing chamber having relatively narrow oblique ribs on its inner walls and, adjacent the outlet, thin, open-spaced, transversely extending members against which the whirling mixture is adapted to impinge obliquely, a metering device for varying the liquid fuel supply, and means for causing 65 said metering device and said air throttle to 70 have equal opening and closing movements but permitting automatic self-closure of the metering device when the draft fails, said means including a stop adjustable at the will of the operator and, coöperating therewith, 75 a disk actuated by flow of the draft current, rigidly secured to the fuel meter and adapted to hold said fuel meter open to the full extent permitted by said stop during normal operating of the device, but permitting self- 80 closing of said fuel meter when the draft current fails, said metering device being formed and arranged to vary the area of the fuel metering passage substantially uniformly and proportionally throughout the 85 range of its adjusting movement, and said throttle valve being formed and arranged to vary the area of the air metering passage in variable proportion.

Signed at New York city, in the county of 90 New York and State of New York, this 9th day of March, A. D. 1915.
